Application March 16, 1937, Serial No. 68,192

Term of patent 3½ years

To all whom it may concern:

Be it known that I, Harry Aull, a citizen of the United States of America, residing at 4520 No. 19th Street, city of Philadelphia, county of Philadelphia, and State of Pennsylvania, have invented a new, original, and ornamental Design for an Elastic Fabric, of which the following is a specification, reference being had to the accompanying drawing, forming part thereof, in which:

Fig. 1 is a face view of a piece of elastic fabric embodying my ornamental design, to which no tension is applied; and

Fig. 2 is a similar view of the reverse face of the elastic fabric of Fig. 1.

The figures disclose the elastic fabric enlarged in the original drawing sufficiently to cause the fabric to appear in full size in the patent copy.

I claim:

The ornamental design for an elastic fabric as shown and described.
